UNITED STATES PATENT OFFICE.

GEORGE H. LAMBERT, OF ASHEVILLE, NORTH CAROLINA.

GOLF-PRACTICE APPARATUS.

Application filed June 26, 1924. Serial No. 722,616.

To all whom it may concern:

Be it known that I, GEORGE H. LAMBERT, a citizen of the United States, residing at Asheville, in the county of Buncombe and 5 State of North Carolina, have invented a certain new and useful Improvement in Golf-Practice Apparatus, of which the following is a full, clear, and exact description.

The object of this invention is to provide 10 a practice apparatus for use of golfers in perfecting their game, the invention being particularly useful for out-of-doors practice.

Prior to this invention, it was common to tether a golf ball and connect it with a 15 teeing apparatus or other fixable element, so that the ball might be hit in the same way as it would be hit in actual play, with the difference that the tether would return the ball to the player at the end of the flight.

20 Devices of this sort have not been altogether satisfactory due to a variety of causes, amongst them the liability of the snarling of the tether and also the inability to obtain a satisfactory return of the ball and its 25 weight of tether when the ball is struck as hard as in actual play.

One of the objects of the present invention is to provide a golf practice apparatus 30 which will adequately meet these and other conditions and yet be reasonably simple, devoid of mechanism exposed to danger and of ready portability, so that the player may take with him the apparatus conveniently and without burden and quickly set it up 35 for practice in any part of the links or green, or elsewhere.

The invention consists of a return spring 40 mounted in a telescopic casing or housing, the casing or its adjunctive parts being provided with a pin, preferably a staple-like pin, that may be readily driven into the ground as and where desired, the telescopic casing being pivotally connected with this pin so that the casing may rise and fall 45 under the impetus of the stroke; the leash or tether and one end of the return spring being connected with the sliding section of the telescopic casing which moves with the spring, so that as the ball flies and the leash 50 or tether follows it, the spring will expand until the force of the blow is expended, and then the spring will react and return the ball to the player and the sliding section of the casing to normal, as I will proceed now to 55 explain and finally claim.

In the accompanying drawings illustrating the invention, in the several figures of which like parts are similarly designated, Figure 1 is a perspective view illustrating the invention and a player ready to make a 60 stroke from a tee. Fig. 2 is an elevation of the apparatus. Fig. 3 is a longitudinal section taken in the plane of line 3—3, Fig. 2. Fig. 4 is a rear end elevation.

The casing comprises a stationary member 1, of cylindrical or other appropriate form, and a movable member 2 telescopically fitted to the member 1. In the member 1 is a block 3 pierced transversely at 4 to receive a staple-like pin 5 which may be bent to shape in position, and by means of its two legs affording not only firm bilateral support for the apparatus to steady it in action and in line with play, and to ensure its firm anchorage, but serving also as a 70 pivot upon which the apparatus may rise and fall under the force of the flight of the ball when struck and upon its return.

The movable member 2 is provided at its outer end with a transverse pin 6 to which 75 one end of a coiled spring 7 is secured, the other end of said spring being secured to a bolt or other anchoring device 8 which is secured in the block 3 in adjusted position, the adjustment being retained by a nut 9 or other means.

On the bolt 8 is arranged a stiff spring 10 80 which is located between spring 7 and the block 3, and serves as a recoil spring, to take up the shock of the spring 7.

On the pin 6 is a yoke or loop 11 to which 85 is secured one end of the leash or tether 12, the other end of the leash or tether having secured to it in any suitable way a golf ball 13.

In using the apparatus, it is anchored in the earth by the pin 5 and the leash or tether laid out in any convenient manner, with the ball placed in position to be struck, care being taken to lay out the leash or tether in such way as to ensure its following the ball without tendency to snarl. The flight of the ball will carry the leash or tether taut and the spring 7 will yield 90 sufficiently to acquire enough force or tension to return the ball when the ball has reached its limit of flight.

As is apparent, the sliding member 2 will 100 follow the spring as it is put under tension by the flight of the ball, and this spring will 110

return the sliding member upon the return of the ball and the shock or recoil will be taken up by the spring 10.

Thus a very compact and practical practice apparatus is provided of small compass and readily carried by the player and readily put in position for use.

As already indicated, the mounting of the telescopic member on its anchoring pin in 10 a pivotal manner provides for the rising and falling of the telescopic member as the ball is struck and as it returns.

The use of the staple-like anchoring pin also serves to prevent the casing or housing 15 from swinging sidewise and out of line when the ball is not hit true.

Making the casing or housing in telescoping sections also prevents wear at the mouth of the casing where the leash or 20 tether is attached.

Variations in details of construction are 25 permissible within the principle of the invention and the spirit and scope of the claims following.

25. What I claim is:—

1. In a golf practice apparatus, in which the ball is suitably secured to a leash or tether and the latter secured to a return 30 spring, a telescopic casing or housing for the return spring.

2. In a golf practice apparatus, in which the ball is suitably secured to a leash or tether and the latter secured to a return 35 spring, a telescopic casing or housing for the return spring, and an anchoring pin for said casing or housing.

3. In a golf practice apparatus, in which the ball is suitably secured to a leash or tether and the latter secured to a return 40 spring, a telescopic casing or housing for the return spring, and an anchoring pin for said casing or housing pivotally connected therewith to permit the casing or housing to rise and fall in play.

45. 4. In a golf practice apparatus, in which the ball is suitably secured to a leash or tether and the latter secured to a return spring, a telescopic casing or housing for the return spring, and a staple-like anchoring pin connected with the casing or housing.

50. 5. In a golf practice apparatus, in which the ball is suitably secured to a leash or tether and the latter secured to a return 55 spring, a telescopic casing or housing for the return spring, and a recoil spring attached to the return spring within the said casing or housing.

6. A golf practice apparatus, comprising a tension spring, a bolt to which it is connected, a fixed block in which the bolt is mounted, a recoil spring interposed between the block and the tension spring, and a telescopic casing or housing for the aforementioned parts. 60

7. A golf practice apparatus, comprising a return spring, a bolt to which it is connected, a fixed block in which the bolt is mounted, a recoil spring interposed between the block and the return spring, and a telescopic casing or housing for the aforementioned parts, the return spring being secured at its leading end to the sliding member of the telescopic casing or housing. 70

8. A golf practice apparatus, comprising a tension spring, a bolt to which it is connected, a fixed block in which the bolt is mounted, a recoil spring interposed between the block and the tension spring, and a telescopic casing or housing for the aforementioned parts, the tension spring being secured at its leading end to the sliding member of the telescopic casing or housing, 80 and an anchoring pin pivotally secured in the block and serving to fix the block in 85 the casing or housing.

9. A golf practice apparatus, comprising a tension spring, a bolt to which it is connected, a fixed block in which the bolt is mounted, a recoil spring interposed between the block and the tension spring, and a telescopic casing or housing for the aforementioned parts, the tension spring being secured at its leading end to the sliding member of the telescopic casing or housing, 90 and a staple-like anchoring pin extending transversely through the block and the casing member in which it is located and serving to unite the two and having pivotal connection with the block and casing. 95

10. In a golf practice apparatus, in which the ball is suitably secured to a leash or tether and the latter secured to a return spring, a telescopic casing or housing for the return spring, and a staple-like anchoring pin pivotally connected with the casing or housing to permit an up and down pivotal movement of said casing or housing and prevent sidewise movement thereof. 100

In testimony whereof I have hereunto 105 set my hand this 25 day of June A. D. 1924.

GEORGE H. LAMBERT.
